R. L. BRETH

VALVE TOOL

Filed Apr. 7, 1922

R. L. Breth Inventor

By *Cadman & Co.*
Attorney

UNITED STATES PATENT OFFICE.

ROBERT L. BRETH, OF BUTLER, PENNSYLVANIA.

VALVE TOOL.

Application filed April 7, 1922. Serial No. 550,338.

To all whom it may concern:

Be it known that I, ROBERT L. BRETH, a citizen of the United States, residing at Butler, in the county of Butler and State of 5 Pennsylvania, have invented a new and useful Valve Tool, of which the following is a specification.

This invention relates to valve removers and more particularly to tools for compressing the spring of an internal combustion engine valve so that the abutment for the spring attached to the valve stem may be removed and the valve lifted from its seat.

The object of the invention is to provide 10 a simply constructed device of this character which may be quickly applied and connected and the parts of which may be taken apart and stored in a comparatively small space when not in use.

With the foregoing and other objects in view which will appear as the description proceeds, the invention resides in the combination and arrangement of parts and in the details of construction hereinafter described 20 and claimed, it being understood that within the scope of what is claimed changes in the precise embodiment of the invention shown can be made without departing from the spirit of the invention.

In the accompanying drawings:—

Figure 1 represents a side elevation with parts broken out and in section of the tool constructed in accordance with this invention, shown applied.

Figure 2 is a top plan view thereof.

Figure 3 is a vertical section taken on the line 3—3 of Figure 1, and

Figure 4 is a horizontal section taken on the line 4—4 of Figure 1.

The tool constituting this invention comprises a clamp bar or base 1 having one end thereof widened and bifurcated, the furcations 2 thereof being designed to straddle the stem of the valve in connection with 40 which the tool is to be used.

Rising from the bar 1 in longitudinally spaced relation are two posts or rods 3 and 4 which are shown having threaded engagement with bar 1 to provide for their removal 45 when the tool is to be collapsed or knocked down.

The post or rod 3 is longer than rod 4 and both of these rods have their upper ends threaded and are equipped with nuts 5 and 6 respectively. 55

A top movable clamp bar 7 is loosely engaged at one end with the threaded upper end of rod 4 above the nut 6 thereof and also engaged with the upper end of rod 3 as is shown clearly in Figure 1. A coiled spring 60 8 is mounted on rod 3 between the nut 5 and the bar 7 and operates to hold the bar in the position shown in Figure 1.

A cam lever 9 is carried by the upper end of rod 3 above bar 7 being fulcrumed on the 65 nut 10 which has threaded engagement with the rod end 3, said nut being adjustable on said rod to vary the tension of spring 8.

The lever 9 has its inner end bifurcated and the furcations 11 thereof are equipped 70 at their free ends with cams 12 eccentrically fulcrumed on nut 10, said furcations straddling said end as is shown clearly in Figure 2 and designed to engage bar 7 when the lever is swung rearward, thereby forcing 75 said bar downward into clamping engagement with the valve shown at V the bifurcated base 1 having been spaced to straddle the valve spring and permitting the cotter pin to be removed so that the valve may be 80 readily taken out.

When the lever is swung back into the position shown in Fig. 1, the spring 8 will operate to return the clamping bar 7 into its extreme upward position ready again for 85 use.

I claim:

A tool of the class described comprising a base bar, spaced rods rising therefrom, a nut adjustably mounted on one of said rods, 90 a cam lever fulcrumed on said nut, a movable bar mounted on said rods and a coiled spring adapted to normally force said movable bar outward.

In testimony that I claim the foregoing as 95 my own, I have hereto affixed my signature in the presence of two witnesses.

ROBERT L. BRETH.

Witnesses:

E. P. PEFFER,
J. R. PENICK.
